GAME APPARATUS

Junius M. Schutte, Chicago, Ill., assignor to Burgess Battery Company, a corporation of Delaware

Application April 10, 1944, Serial No. 530,256

6 Claims. (Cl. 273—129)

This invention relates to a game apparatus, particularly to an apparatus for playing a game similar to golf. The game is adapted especially to be played indoors upon the carpet or floor, but it may be played as well outdoors upon a lawn or any other suitable surface.

It is the object of the invention to provide a game apparatus of the character mentioned which is simple and convenient to manufacture and is capable of developing considerable skill and interest on the part of the player.

Briefly, the apparatus comprises a device which assumes the role of a golf club, and includes an elongated shaft adapted to be held upright by the hand and to rest at its lower end upon the carpet or other playing surface. The shaft has a ball-propelling member pivotally supported thereon near the lower end thereof and has a striking member in the form of a hollow cylinder which is freely slidable upon the shaft above the ball-propelling member. In operation, one end of the ball-propelling member is placed adjacent a suitable ball upon the playing surface, and the striking member is allowed to drop from a suitable height. In its descent, the latter member strikes the opposite end of the ball-propelling member with the result that the latter imparts a propelling impulse to the ball. A suitable goal, or series of goals, is provided, and the object of the game, as in golf, is to get the ball into the goal, or successively into a series of goals, in the smallest number of strokes.

In the drawing:

Fig. 1 is a perspective view of the game apparatus in the position in which it is used;

Fig. 2 is an enlarged perspective view of the lower portion of the apparatus in a similar position;

Figs. 3 and 4 are side and rear views respectively of the lower portion of the apparatus in a similar position;

Fig. 5 is a side sectional view of the lower portion of the apparatus immediately after it has been operated;

Fig. 6 is a side view of the lower portion of the apparatus after it has been operated, showing the goal and in dotted lines indicating the path of travel of the ball and the position of the ball-propelling member prior to operation; and

Fig. 7 is a front sectional view of the lower portion of a modified form of the apparatus.

Referring to Fig. 1, the apparatus comprises a slender shaft 10, preferably having a knob 11 at the upper end thereof and being adapted to

rest upon the playing or supporting surface 12 at the lower end thereof.

A ball-propelling member 13, in the general form of a plate, is supported pivotally upon the shaft at a point adjacent and spaced from the lower end of the latter. An opening 14 is provided in the propelling member through which the shaft 10 passes. Sufficient clearance is provided between the edges of the opening and the shaft to permit the pivotal movement of the propelling member. The method for supporting the propelling member 13 is shown more clearly in Fig. 2. A pin member 15 passes through the shaft 10 in a direction transversely to the axis of the shaft, and passes underneath the propelling member 13, the end portions 16 of the pin being bent back upon themselves to form loops within which the edge portions of the propelling member are held. The edges of the propelling member may be notched as shown in Fig. 2, whereby the propelling member is held firmly and does not move relatively to the pin. The opening 14 and the pin 15 are displaced longitudinally of the propelling member 13 from the mid-portion thereof, whereby the portion of the propelling member extending in one direction from the supporting pin, which will be called the forward direction, is heavier than the rearward portion, and the propelling member normally assumes an inclined position with the forward end resting upon the supporting surface. The pin 15 is freely pivotal with respect to the shaft and the described inclined position is readily assumed by the propelling member 13 when external forces are removed.

The propelling member 13 is shown in the drawing as being slightly curved instead of planar. The curvature is such that greater lift is given to the ball than if the member were planar. It is also shown as being relatively wide at its mid-section and becoming gradually narrower toward its forward end, and becoming narrower relatively quickly and then continuing at substantially the same width toward its rearward end. These shape features are not of importance, and the propelling member may be planar and of rectangular or any other suitable configuration. The only requirements are that its mass be so disposed upon the supporting pin that the forward end will normally drop to the supporting surface, and that this end has sufficient width to present a suitable propelling surface to the ball, which is shown at 17.

A striking member 18, in the general form of a hollow cylinder, is mounted in telescoping re-

lationship upon the portion of the shaft 10 above the propelling member 13, and is freely slid able along the length of the shaft between the knob 11 and the propelling member 13.

One or more goal members are provided, which may be like that shown in Fig. 6, which comprises a member 20 which is annular in its general shape and has a flat bottom surface adapted to rest upon the playing surface 12 and an upwardly sloping top surface leading to the central opening 21, which is of a size suitable to receive and retain the ball 17. The opening 21 is the goal and will be called a hole.

In operation, the upper end of the shaft 10 is grasped in one hand and the shaft held in the upright position resting at its lower end upon the playing surface 12. The propelling member 13 assumes the inclined position described heretofore and its forward edge rests upon the supporting surface, as shown in Figs. 1 to 4. The ball 17 is placed upon the supporting surface 12 in front of the propelling member and in contact therewith or in sufficiently close proximity thereto that the propelling member will give the ball a satisfactory impact when it is actuated. The striking member 18 is held in an elevated position by the other hand, as indicated in Fig. 1. The striking member 18 is then released, whereupon it drops by gravity and strikes the rearward portion of the propelling member. The propelling member is thereby given a rapid pivotal movement from the inclined position shown in Fig. 3 to the substantially horizontal position shown in Fig. 5, and the ball 17 is simultaneously given a propelling impulse. An operation of this character will be called a stroke.

The ball is preferably of lightweight construction, such as cork, hollow rubber, etc. so that it will be propelled readily by the impact and its inertia will not carry it undesirably far, since the game is intended primarily to be played in a relatively small space. In the same manner, the propelling member 13 is preferably of lightweight construction such as a lightweight metal, thin hard-pressed paperboard, etc., so that it will respond readily to the impact imparted to it by the striking member. The propelling member may also be made flexible so that it can be bent by the hand to give to the ball the amount of lift desired by the player.

By properly positioning the device relatively to the ball, the direction of travel of the ball toward the goal is controlled, and by regulating the height from which the striking member 18 is dropped, the force of the impulse and the distance of travel of the ball is controlled. If a maximum distance is desired, the striking member is raised to the full height of the shaft 10; that is, until it makes contact with the knob 11. If the ball rests only a short distance from the hole it may be necessary to raise the striking member only slightly, for example, a distance equal to its own vertical length, above the point where it comes to rest after striking the propelling member.

The action involved in a stroke which results in the ball entering a hole is illustrated in Fig. 6. The propelling member 13 is shown in dotted lines in the unoperated position with the forward edge thereof resting upon the supporting surface 12 and the ball 17 substantially in contact with the propelling member. The striking member 18 strikes the propelling member and comes to rest in the position shown, while the propelling member rapidly moves from the un-

operated position to the operated position, shown in full lines. The ball is given an impulse and moves in the trajectory indicated in dotted lines. It is lifted from the supporting surface and propelled forward at the same time. It then drops to the supporting surface and rolls to the edge of the goal member 20, then up the sloping surface of the latter and into the hole 21.

As stated heretofore, the object of the game is to control the direction and force of the impulse so accurately as to cause the ball to enter the hole 21. If the object is not attained in the first stroke, a second stroke is taken while the ball lies in the position at which it came to rest from the previous stroke, and this is repeated, as in the ordinary game of golf, until the ball is finally caused to enter the hole 21. With the apparatus described, considerable skill can be developed, and the interest in the game is thereby increased. As stated heretofore, several goals may be employed if desired. For example, nine consecutively numbered goals may be distributed in various locations, and various obstacles, such as pillows, etc., may be placed between successive goals, to simulate a nine-hole golf course.

A modification of the apparatus is shown in Fig. 7, which modification is adapted for controlling the lift which is given to the ball. In this device, the portion of the shaft below the support for the propelling member is of variable length. The parts of the device are similar to those of the device shown in Figs. 1 to 6, and comprise a shaft 25 having a pin 26 passing therethrough and supporting a propelling member 27. The portion of the shaft below the supporting pin 26 includes a section which consists of a helically coiled wire, or spring 28. The shaft 25 has a reduced portion 29 projecting from a shoulder 30 at the lower end of the shaft, and the helical wire is forced over the reduced portion 29 and into contact with the shoulder 30. The diameter of the reduced portion 29 is normally somewhat greater than the inside diameter of the helical wire so that there is a firm grip between the two parts.

In the same manner, the member 31, which serves as the bottom tip for the shaft 25 and is preferably of the same lateral contour and dimensions as is the shaft, has a reduced portion 32 projecting upwardly from a shoulder 33. The lower end portion of the helical wire member 28 is fitted over the reduced portion 32 and against the shoulder 33 in the same manner as the upper portion cooperates with the end portion of shaft 25.

In the operation of this modification, if it is not desired to accentuate the lift given to the ball, the manipulation is the same as with the device shown in Figs. 1 to 6. If a greater lift is desired, the shaft is urged downward by the hand which grasps its upper end portion, whereby the helical wire member 28 is compressed and shortened, bringing the pin support 26 in closer proximity to the playing surface 34 and causing the inclination of the propelling member from the horizontal to be reduced, whereby the ball is caused to arch higher in its travel toward the goal. It will be appreciated that such higher arching may be desirable under a number of circumstances, as when the ball lies in a position close to the goal. In such circumstances, it may be desirable to cause the ball to travel the entire distance through the air and not undergo any rolling upon the playing surface.

While but two modifications of the apparatus

are described and illustrated, it is understood that other changes and modifications may be made without departing from the scope of the invention as the same is defined in the appended claims.

I claim:

1. A game apparatus, comprising a shaft adapted to be rested at the lower end thereof upon a surface, a support carried by said shaft at a point adjacent and spaced from said lower end, a plate member resting intermediate its ends upon said support and being in pivotal relationship with said shaft, said plate member having an opening therein through which said shaft freely passes, the portions of said plate member on opposite sides of said support being of unequal mass whereby said plate member normally rests upon said support in an inclined position, said support being spaced from the lower end of said shaft a distance such that when said shaft rests upright on said surface the lower end of said plate reaches substantially to said surface, and a striking member locally engaging said shaft above said plate member, said striking member being freely slideable longitudinally on said shaft and adapted to strike said plate member.

2. A game apparatus, comprising a shaft adapted to be rested at the lower end thereof upon a surface, a game piece propelling member pivotally supported intermediate its ends on said shaft at a point spaced from said lower end of said shaft, the opposite end portions of said propelling member extending transversely of said shaft beyond the opposite sides thereof, said propelling member in the upright position of said shaft, having one end portion normally extending downwardly to a point substantially as low as the lower end of said shaft and the opposite end portion extending upwardly from said point of

support for said propelling member, and a striking member engaging said shaft above said propelling member, said striking member being freely slideable longitudinally on said shaft and adapted to strike said propelling member.

5. 3. A game apparatus, comprising a shaft adapted to be rested at the lower end thereof upon a surface, a game piece propelling member pivotally supported on said shaft at a point spaced from said lower end, and a striking member freely slideable longitudinally along said shaft above said propelling member, said propelling member, in the upright position of said shaft upon said surface, having an end portion normally extending downwardly from said point of support and adapted to propel a game piece and a second portion extending upwardly from said point of support and adapted to be struck by said striking member.
10. 4. A game apparatus as claimed in claim 3, in which the portion of the shaft between the lower end thereof and the support for the propelling member is of adjustable length.
15. 5. A game apparatus as claimed in claim 3, in which the game piece propelling member is of flexible construction.
20. 6. A game apparatus, comprising a shaft adapted to be rested at the lower end thereof upon a surface, a game piece propelling member, means for pivotally supporting said propelling member at a point spaced from said lower end of said shaft, and a striking member freely slideable longitudinally along said shaft above said propelling member, one portion of said propelling member being adapted to propel a game piece and a different portion of said propelling member being adapted to be struck by said striking member.

JUNIUS M. SCHUTTE.
